Geo. P. Kimmel
ATTORNEY.

UNITED STATES PATENT OFFICE.

CATHERINE V. KEETHES, OF ST. LOUIS, MISSOURI.

ORNAMENTAL FLOWER PIN.

Application filed June 18, 1928. Serial No. 286,189.

This invention relates to ornamental flower pins, but more particularly to a combined brooch and flower holder for connection to wearing apparel, and the object of 5 the invention is to provide in a manner as hereinafter set forth, an article of such class into which flowers may be inserted and secured without detaching the article from the garment whereby the flowers may be attached at the desired position on a person and will not become deranged during the 10 course of an evening.

Further objects of the invention are to provide in a manner as hereinafter set forth 15 an ornamental flower pin which is highly efficient for its intended purpose, strong, durable, compact, simple in its construction and arrangement pleasing to the aesthetic sense, both ornamental and useful, easily 20 positioned upon the clothing, always present for emergency use and comparatively inexpensive to manufacture.

With the foregoing and other objects in view the invention consists of a novel construction, combination and arrangement of 25 parts as hereinafter more specifically described and illustrated in the accompanying drawings, wherein is shown an embodiment of the invention, but it is to be understood 30 that changes, variations and modifications may be resorted to which fall within the scope of the claims hereunto appended.

In the drawings wherein like reference characters denote corresponding parts 35 throughout the several views:

Figure 1 is a side elevation of the device in closed position in accordance with this invention.

Figure 2 is the same as Figure 1 illustrating the device in open position.

Figure 3 is one end view.

Figure 4 is the opposite end view.

Figure 5 is a section on line 5—5 of Figure 1 looking in the direction of the arrow.

Referring to the drawings in detail, a flower pin in accordance with this invention comprises outer and inner substantially rectangular plates 1 and 2 respectively. The plates are of the same thickness, and width, 50 but the outer plate 1 is substantially longer than the inner plate 2. The outer face of plate 1 may be ornamented in any manner, as indicated at 3. The surface ornamentation makes the flower pin adaptable for general wear, while at the same time the pin

will be handy for attaching flowers to the apparel when desired.

Extending from one end of the outer plate 1 and secured to the inner face thereof is a hinge arm 4 which is of the same width as the plate. The arm projects at right angles to the plate and is flush with the end thereof. The inner end of the arm is formed with a pair of spaced opposed eyes 5, 6. The openings of the spaced eyes are in alignment for 65 reception of the pivot pin 7 to be hereafter referred to.

Adjacent the other end of the plate 1 and extending from the inner face thereof is a hooked-shaped keeper for coacting with a latching member 9, for latching plates 1 and 2 together. The latching member 9 is substantially of Z-shaped contour, formed of 70 resilient material and includes oppositely disposed, laterally extending, inner and 75 outer arms 10, 11 respectively.

The inner arm 10 of the latching member is secured to the inner face of the inner plate 2. The member 9 projects at right angles to the plate 2 and flush with the end thereof. 80 The member 9 is spaced inwardly from the end of plate 1. The outer arm 11 extends in a plane parallel to the plane of the arm 10. The free end of the outer arm 11, when in coupled relation is flush with the adjacent end of plate 1. The latching member being resilient is free to be flexed in any direction. When plates 1 and 2 are coupled at the opposite end and assume a parallel relation to each other the arm 11 of the latching 85 member may be flexed over the lip of the keeper 8 and will automatically seat itself within the recess of the keeper, thereby latching the plates 1 and 2 together.

On the opposite end of the plate 2 from the latching member is a hinge arm 12, extending at right angles to the plate and flush with the ends thereof. The arm is of the same width as the plate 2 and also is the same width as the arm 4 and extends in the same plane as said arm. On the outer end of the arm 12 and extended from the edge thereof is an eye 13 which is located centrally with respect to the side edges of the arm 12. The eye 13 is interposed between 100 and registers with the eyes 5, 6 of the hinge arm 4. A pivot pin 7 extends through the registering eyes 5, 13 and 6 respectively whereby the plates 1 and 2 are pivotally 105 coupled together.

A row of triangular shaped piercing barbs 14 and 15 are disposed at right angles to the opposed inner faces of the plates 1 and 2 respectively. The bases of the barbs of each row are attached to the opposed inner faces in spaced relation to each other and each row extends in central longitudinal alignment with respect to the faces to which they are attached. The bases of the row 10 14 are staggered with respect to the bases of row 15. The foregoing construction will cause the projecting triangular barbs to extend in the same plane but in opposite directions. Since the bases of the opposed rows 15 are staggered, the vertices 16 and 17 of the opposed rows will be staggered. The vertices 16 will overlap vertices 17 and extend into the spaces between the barbs of the opposite rows. The sharp vertices will pierce or extend between the stems of the flowers that are abutting the opposed inner faces of the plates and hold them securely in position when the said plates are in the latched position as shown in Figure 1.

An attaching member for connecting the article to the wearing apparel is indicated generally at 18. The retaining member comprises a pin 19 extending longitudinally of the outer face of the inner plate 2 when in retaining position as shown in Figure 1 of the drawings. The pin is adapted to be positioned in spaced relation and parallel to the outer face of plate 1 when it is attached to the wearing apparel. One end of the pin 35 is pivoted as at 20 to one end of the outer face of the plate 2, while the pointed end engages with and seats within the body of a hook 21 which is secured adjacent the end of the outer face of plate 2. The hook 21 is adjacent the latching member 9 and the hinge 20 is adjacent the hinge arm 12.

The plates 1 and 2 provide a pair of clamping members carrying means on the opposed faces thereof constituting retainers

for the stems of the flowers, such means are 45 the oppositely disposed rows of spaced piercing barbs which coact with the hinged and latched ends of the plates for clamping the flowers with the plates.

What I claim is:—

1. An article for the purpose set forth comprising a pair of opposed plates, a pair of right angularly disposed hinge arms secured to the inner faces at one end of said plates, means at the inner ends of said arms 55 for pivotally connecting said arms together, a resilient latching member extending at right angles and secured to the inner face of one of said plates at its other end, a keeper secured to the inner face of the other of said plates to engage with said resilient member for latching said plates together, and a row of spaced triangular retainers secured to the inner face of each plate, the retainers carried by one plate being staggered with respect to the retainers on the other plate.

2. An article for the purpose set forth comprising a pair of opposed plates, a pair of right angularly disposed hinge arms secured to the inner faces at one end of said plates, means at the inner ends of said arms 70 for pivotally connecting said arms together, a substantially Z-shaped resilient latching member extending at right angles and secured to the inner face of one of said plates at its other end, a keeper secured to the inner face of the other of said plates to engage with said resilient member for latching said plates together, and a row of spaced 75 triangular retainers secured to the inner face of each plate, the retainers carried by one plate being staggered with respect to the retainers on the other plate.

In testimony whereof, I affix my signature 85 hereto.

CATHERINE V. KEETHES.
